UNITED STATES PATENT OFFICE

JOSEPH JEAN MARIE GUEUX, OF PARIS, FRANCE

MEASURING DISTRIBUTOR FOR LIQUIDS

Application filed December 26, 1922, Serial No. 609,042, and in France December 28, 1921.

My invention relates to a device for the supply of liquids in measured volumes, wherein the principal features consist in obviating all leakage of the liquid, and also in 5 providing for the constant accuracy of the supply, even should the apparatus not be disposed in the exact vertical position. Further, I have taken special measures to prevent all fraudulent practices on the part of the 10 buyer or the seller.

My said supply apparatus consists essentially of a transparent bell which contains the liquid to be supplied; within the said bell is disposed a vertical overflow tube of suitable 15 height containing a suitable supply tube in the coaxial position; surrounding the said overflow tube are disposed various cup-shaped vessels or troughs, at suitable levels, and leading from each trough is a special 20 conduit connected with a feeding hose, through the medium of an independent cock. Each cock is provided with a separate register and with means for cutting off the pump or the supply cock as soon as the feeding has 25 commenced.

The appended drawings which are given by way of example show a constructional form of my said apparatus, together with various details which may be optionally employed.

Fig. 1 is a general elevational view of the apparatus.

Fig. 2 is an axial sectional view of the upper part of the same taken on the line II—II 35 of Fig. 3.

Fig. 3 is a section on the line III—III of Figs. 1 and 2.

Fig. 4 is a section, on a larger scale, of certain parts shown in Fig. 2.

Fig. 5 is a sectional view on the line V—V of Figs. 1 and 2.

Fig. 6 is a detail of the safety means associated with the pump hand wheel.

Fig. 7 is an enlarged detail in vertical section of the safety means.

Fig. 8 is a view similar to Fig. 7 showing the safety means operating in connection with a valve for controlling the liquid flow and replacing the pump.

50 The feeding device which is shown in Figs.

1 to 5 comprises a transparent bell-shaped member 1 with rounded top and with the flanged bottom 2 resting upon a metal plate 3 through the medium of the packing member 5. The said bell is maintained upon said plate by the ring 6 which is attached by the screws 7, the packing member 4 being interposed.

The discharge or overflow tube 9, coaxial with the said bell, extends through the plate 3 and surrounds the supply tube 10. At the top of the said discharge tube is disposed the small cup or trough 73 and at a certain distance above the latter is mounted a small horizontal disk 72.

At the lower end of the said overflow tube is an enlarged portion 8 to which is connected the pipe 11 returning to the main tank of the apparatus. The supply tube 10 is extended through the enlarged portion 8 and connected with tube 12 communicating with a suitable pump 21 which is controlled from the exterior by the hand wheel 87. Obviously, the supply tubes 10 and 12 are quite separate from the overflow members 8, 9 and 11.

At the lower part of the said bell, and leading from the plate 3, is an emptying conduit 17 provided with a cock 18 and communicating with the return pipe 11.

Around the overflow tube 9 (Fig. 3) are disposed at suitable heights the cups or troughs 101, 102, 103, 104 and leading therefrom are the respective vertical tubes 13, 14, 15, 16 which pass through the plate 3 through suitable packing members and terminate at the respective independent cocks 23, 24, 25, 26 (Figs. 3 and 5); to the latter are connected the respective discharge conduits 31, 32, 33, 34 (Fig. 5) which lead to a common collecting chamber 35, leading from which is the conduit 30 (Fig. 2); to the latter is connected a flexible hose 37, ending optionally in the cock 38. The four cocks 23, 24, 25, 26 are of like construction. One cock 24 is shown in detail in Fig. 4.

The liquid contained in the bell is delivered to the cock by the tube 14. The clack valve 39 of the cock is so disposed that the pressure of the liquid will urge it upon its seat 41, this

action being aided by the spring 42 surrounding the valve stem 40.

The said stem extends outwardly of the cock and has at the end a shoulder 90 serving as the abutment for a spring 43 which urges inwardly a movable ring 91 mounted on the said stem 40 and in contact with a lever or handle 44 which is pivoted to the bracket 45 secured to the main body of the cock. Upon

10 the said lever is mounted a stud 46 engaged in a horizontal slot 47 in the valve stem 40.

To the handle 44 is pivoted a push-piece 74 which is adapted to fold up by turning on its pivot 75. Above its pivotal point on the

15 bracket 45, the handle 44 carries a stud 48 which is engaged in a vertical slot 49 in a pawl 50 coacting with a ratchet wheel 65 mounted on the shaft of an adding counter or meter 58. Below its pivotal point on the

20 bracket 45, each lever 44 carries an axle 51 inserted between the branches of a fork which is mounted on the end of a rod 52 adapted to control through the medium of a bell crank lever 53 (Figs. 2 and 5) a closing

25 member or shutter 56 which is connected with the lever 53 by a sliding piece 55; said shutter is slidable in suitable grooves behind a window 57 in the casing of the apparatus in such manner as to be visible through a win-

30 dow 57 when the handle 44 is operated.

Since there are four feeding cocks 23, 24, 25, 26, there will obviously be provided four handles 44, each provided with a push-piece 74. At the upper end of each handle 44 is a

35 toe 19 which upon actuating the handle will successively engage the notches 27 and 28 of a retaining lever 59 which is pivoted to the main body of the cock. The toe 19 may be

30 disengaged from the said notches by raising the lever 59 which extends outwardly

40 (Fig. 1).

A safety device is provided in order to prevent any liquid being supplied to the bell while the feeding to the exterior is taking place; as shown in Figs. 2, 3 and 5, this device consists of a lower transverse shaft 77 extending below the four handles of the cocks 44.

Opposite each handle 44, the shaft 77 carries an arm 76 of suitable shape, which is turned down when the corresponding handle 44 is operated. The shaft 77 is further provided at its centre with an arm 78 to which is pivoted the rod 79, mounted in a guide 80 and urged by a spring 105, and having at the end the sleeve 81 (Fig. 6). Within the said sleeve is disposed the spring 82 in contact with a pin 83 which is held in the said sleeve by a stud 84 engaged in a slot 85 in the said

60 pin; the pin 83 cooperates with a gear wheel 86 which is secured to the wheel 87 actuating the feed pump 21.

Fig. 8 illustrates a form of safety device identically the same in fundamental structure to the form of the device illustrated in

Fig. 7, but rearranged to adapt it for use in controlling an ordinary valve such as indicated in dotted lines at 22. In this arrangement the gear wheel 86^a of the hand wheel 87 is secured to the plug of the valve.

The operation is commenced by completely filling the bell 1 with the liquid. For this purpose, all the cocks 23, 24, 25, 26 are closed, and the pump 21 is operated.

The liquid withdrawn by the said pump is 75 discharged into the pipes 12 and 10, and when issuing from the latter, the liquid is caused to impinge upon the disk 72 whereby the stream is suitably spread out.

In this manner the said bell is gradually 80 filled, and when the liquid attains the level of the upper trough 73 it will be discharged by the overflow tube 9 and will return through the conduit 11 to the main tank. Should the pumping now cease, the liquid will come into 85 equilibrium at the level P—0 (Fig. 2).

The spacing of the troughs 101, 102, 103, 104 is such that the amount of liquid comprised between a given trough and the level P—0 shall have a stated value, for instance 90 an integral number of liters. In this manner, there will be 20 liters of liquid between the level P—20 of the trough 104 and the level P—0; 15 liters between the level P—15 of the trough 103 and the level P—0; 10 liters 95 between the level P—10 of the trough 102 and the level P—0; and 5 liters between the level P—5 of the trough 101 and the level P—0; obviously, any other suitable arrangement may be employed.

100 By operating for instance the handle 44 corresponding to the cock 24 (Fig. 4), the stud 46 on said handle will move in the slot 47 of the stem 40 of the cock, but without moving the said stem. However the pawl 50 acts 105 from the beginning upon the ratchet wheel 65 of the meter 58, which thus registers one unit. Continuing its motion, the handle 44 actuates the stem 40 of the cock 24 and opens the valve 39; the liquid comprised between the levels 110 P—0 and P—10 will now be discharged through the pipe 14; it will enter the main chamber 35 and will be discharged thence through the hose 37.

115 Since the handle 44 of the cock 24 has thus been operated, the rod 52 pivoted thereto will have been driven back, and the shutter 56 connected to the rod by the member 53 will appear before the window 57. Upon the said shutter there is marked the indication for 10 liters, corresponding to the amount supplied by the cock 24. The purchaser will thus observe the amount of liquid which he receives.

120 When the handle 44 is operated, its arm 76 is driven back, and causes a slight rotation of the shaft 77; the rod 79 descends against the action of the spring 105 and the pin 83 at the end of the said rod will engage the teeth of the wheel 86, thus locking the pump and preventing all further supply of liquid.

Obviously, when the pin 83 (Fig. 6) coincides with one of the teeth of the wheel 86, this wheel is not at once locked, but when the smallest motion is imparted to the wheel 87, the arm 83 will be impelled outwardly by the spring 82 and will enter a recessed portion, thus locking the pump. The end 19 of the operated handle 44 engages in and is held by the notches 27 and 28 of the lever 59, and the push-piece 74 may therefore be released without the return of the handle 44 to the first position.

On completion of the feeding operation, the lever 59 is raised in order to disengage the handle 44. The valve 39 urged by its spring 42 will return upon its seat; the rod 79 urged by the spring 105 will now rise and its pin 83 will be disengaged from the wheel 86. The pump may now be operated in order to bring 20 the liquid in the bell to the level P—0.

When brought back by the handle 44, the rod 52 turns the bell-crank lever 53 to which it is pivoted and the shutter 56 which was in coincidence with the window 57 will now 25 have disappeared and is no longer visible from the exterior. The apparatus is now ready for the next feeding operation.

Obviously, if it is desired to supply 20 liters instead of 10, it will suffice to operate 30 the handle 44 corresponding to the cock 26, and all the aforesaid movements will be effected in like manner; the shutter indicating the number 20 will appear before the window 57; the meter for the cock 26 will register one unit, and the pump 21 will be stopped 35 until the handle 44 of the said cock has returned to the starting point.

When it is desired to entirely empty the 40 said bell in order to remove the same, the emptying cock 18 is opened, and the whole contents of the bell will be discharged into the return conduit through the pipe 11. Should the owner of the apparatus desire to 45 ascertain the amount of liquid which has been supplied during a stated period, he notes the indications of the number of liters supplied each time that the cock corresponding to the given meter is opened, and he then adds together the four figures thus obtained.

Obviously, my said apparatus is susceptible of numerous constructional modifications without departing from the principle of the invention. For example the bell 1 may be replaced by a glass cylinder closed at the 55 top by a tight metal disk.

As above stated, if a supply of liquid under pressure is available, I may dispense with the pump 21 and substitute a cock 22 mounted on the conduit 12. In this event, the overflow conduit 11 should be connected with a special tank, which is not subjected to the ordinary pressure.

I claim—

1. An apparatus for dispensing predetermined quantities of liquid comprising a cham-

ber, a liquid supply pipe communicating with and arranged axially and terminating within the chamber, an overflow pipe arranged about the supply pipe, and a plurality of troughs arranged about the overflow pipe, at various points thereon, pipes communicating with the troughs, distributing valves associated with the last mentioned pipes, a common distributing pipe connected with said valves, means for supplying liquid to the chamber through the liquid supply pipe, actuating means for the distributing valves, and means controlled by said actuating means for locking the liquid supply means against operation.

2. An apparatus as claimed in claim 1 characterized in that the actuating means for each distributing valve includes a handle, and a totalizer actuated by each handle for indicating the number of actuations thereof.

3. An apparatus as claimed in claim 1 characterized in that the actuating means for each distributing valve includes a pivoted handle lever, means connecting each lever with the valve associated therewith whereby to actuate the latter in response to an operation of the handle lever, a totalizer arranged at the axis of each lever for indicating the number of operations thereof, and means for actuating each totalizer in response to the movements of the handle lever associated therewith.

4. An apparatus as claimed in claim 1 characterized by the provision of distributing valve indicating means operated by the actuating means for the distributing valves.

5. An apparatus as claimed in claim 1 characterized in that the locking means for the liquid supply means includes a notched member carried by the liquid supply means, means adapted to enter the notched member to lock the liquid supply means against operation, and means actuated in response to a manipulation of any of the distributing valves to engage the last mentioned means in the notched member.

6. An apparatus for dispensing pre-determined quantities of liquid comprising a chamber, a vertical overflow pipe extending axially through the chamber, a liquid supply pipe extending upwardly within the overflow pipe, liquid supplying means connected with said supply pipe, a plurality of trough-like elements arranged about the overflow pipe at predetermined points thereon, a liquid dispensing conduit, individual pipe connections between the trough elements and the dispensing conduit and valves controlling the passage of liquid from the individual pipe connections to the dispensing conduit, means for actuating each valve, said means including a pivoted lever connected with the valve, a locking device for the liquid supplying means actuated by said lever, and means for retaining said lever in the position the latter assumes when the valve is open.

7. An apparatus as claimed in claim 6 characterized by the provision of a window, indicating devices movable to a position visible through said window, and means connecting each indicating device with one of the valve actuating levers.

In witness whereof I affix my signature.
JOSEPH JEAN MARIE GUEUX.
